UNITED STATES PATENT OFFICE.

AUGUSTINE DAVIS, JR., OF COVINGTON, KENTUCKY, AND ARTHUR L. BETTS, OF CINCINNATI, OHIO; SAID BETTS ASSIGNOR TO SAID DAVIS.

MOUNTING FOR VEHICLE-TANKS.

1,329,039.

Specification of Letters Patent. Patented Jan. 27, 1920.

Application filed July 22, 1919. Serial No. 312,529.

To all whom it may concern:

Be it known that we, AUGUSTINE DAVIS, Jr., and ARTHUR L. BETTS, citizens of the United States, and residents, respectively, 5 of Covington, in the county of Kenton and State of Kentucky, and of Cincinnati, in the county of Hamilton and State of Ohio, have invented a new and useful Mounting for Vehicle-Tanks, of which the following 10 is a specification.

The invention is an improved mounting for the tanks of tank wagons and trucks. One of the objects is to provide a standard 15 mounting which can be applied to chassis or under-frames of various widths. The object is also to provide a strong and simple construction, not subject to springing or looseness under the conditions of wear and strain to which it is subjected, and insuring a low 20 center of gravity for the load. Another object is to provide a composite bolster comprising a channel with raised ends and a cradle block therein, which is braced against overhanging weight on running 25 boards carried by said raised ends. Still another object is to strap the tank to the mounting in such manner as to spring neither the sills nor the bolster and to admit of various widths of tanks being used. 30 With these and other objects in view the invention comprises the parts, improvements and combinations hereinafter described in connection with the accompanying drawings and more particularly pointed 35 out in the claims.

In the said drawings:

Figure 1 is a side elevation of the mounting with tank on the chassis or under-frame of a vehicle;

Fig. 2 is a vertical cross-section on the line 2--2 of Fig. 1;

Fig. 3 is a vertical section on the line 3--3 of Fig. 2; and

Fig. 4 is a vertical section on the line 4--4 of Fig. 2.

The side members of a chassis are designated 1. Resting thereon and secured thereto in a suitable manner are wooden side 50 sills 2 forming part of the mounting. Bolsters 3 are supported transversely on the sills, with their ends projecting outwardly.

A suitable number of these bolsters are provided at intervals. Each bolster comprises an upwardly-facing bolster channel 4 55 in contact with the sills, and a cradle-block

5 fitting at the bottom in the channel and having a curved seat 6 in the top to receive the tank 7.

The cradle-block 5 has slots or recesses 8 cut therein, formed so as to extend lengthwise of the bolster just above the top of the iron 4, over and extending beyond both sides of the sills. Fastenings in the form of U-bolts 9 are inserted in these slots, straddling the channel 4 and passing downward 65 at both sides of each sill. Their lower ends pass through openings in angle fittings 10 on the sides of the sills, where they are drawn tight by nuts 11. The fittings 10 are secured to the sills by horizontal bolts 12, 70 and are located below and clear of the bottoms of the bolster-irons so that when the wood of the sills shrinks and the play is taken up at the nuts 11, the load will not be brought upon the fittings and thence upon 75 the bolts 12, but will always be borne solidly by the sills. The connection of the bolsters to the sills is such that the sills can be set farther in or out with respect to the bolsters to fit various widths of chassis.

The ends 13 of the bolster-channel are raised to receive running-boards 14 at the sides of the tank, and within the channels beneath the running-boards are placed filler-blocks 15. The inner portions of these filler-blocks overlap the top of the cradle-block 5 and are secured thereto by lag screws. In this manner an effective bracing is provided for the overhanging ends of the bolster-channels, without complication and without 80 taking up additional vertical space. Bolts passing through the running-boards, the filler-blocks and the end portions of the bolster-channels, secure the running-boards to the bolsters and also assist in holding 85 the bolsters and filler-blocks in the channels.

The tank is tied in place by straps 16 disposed in pairs, the rod terminals 17 of which pass at opposite sides of the bolsters, and are anchored to lugs 18 welded to the 100 under side of the bolster-channel, outwardly from the sills and the fittings 10. The ends of the terminals of each pair pass through openings in a half-round stirrup-bar 19 which is caught beneath or inwardly of 105 the lug, tightening nuts 20 being provided on the terminals beneath the stirrup-bar. It is important to fasten the straps to the bolster-channels rather than to the sills, which would be liable to cant under the pull; 110

there is, however, a tendency to spring the channel, and this we overcome by welding against the flanges of the channel, at the central region thereof between the sills, 5 plates 21, which increase the depth of this portion of the channel and hold it rigid against bowing. The straps passing in pairs at opposite sides of the bolsters and connected by the stirrup-bar 19 beneath the 10 lugs 18 insure a secure holding of the tank and can assume any angle depending upon its width.

While the preferred form of the invention has been described in detail, we do not 15 necessarily limit ourselves thereto, as vehicle mountings embodying the invention of somewhat different form or for different purposes may be designed.

What we claim as new is:

20 1. A mounting for vehicle tanks comprising the combination of sills, a bolster-channel thereon, a cradle-block seated in the bolster-channel and having slots above the top thereof and over the sills, fittings upon opposite sides of the sills, and U-bolts within 25 said slots and straddling the channel with their ends secured to said fittings.

2. A mounting for vehicle tanks comprising sills, bolster-irons thereon, cradle-blocks 30 on the bolster-irons and having slots above the top of the irons and over the sills, fittings upon opposite sides of the sills, and fastenings within said slots straddling the bolster-irons and secured to said fittings.

3. In a tank vehicle, the combination of a 35 bolster, a tank cradled in the bolster, a pair of tank-straps the terminals of which pass at opposite sides of the bolster, the bolster projecting outward between the pairs of terminals, and anchorages for the terminals on the bolsters.

4. In a tank vehicle, the combination of a 40 bolster-iron, a cradle-block thereon, lugs on the bolster-iron, and a pair of tank-straps having their terminals passing at opposite sides of the bolster-iron and cradle-block and anchored to said lugs.

5. In a tank vehicle, the combination of a 45 bolster, lugs on the under side thereof, a pair of tank-straps having their terminals passing at opposite sides of the bolster, and stirrup-bars on the strap-terminals caught beneath said lugs.

6. In a tank vehicle, the combination of

sills, fittings upon opposite sides of the sills, 55 a bolster, bolts connecting the bolster with said fittings, lugs on the bolster located outwardly from the sills, and a pair of tank-straps the terminals of which pass at opposite sides of the bolster and connect with 60 said lugs.

7. In a tank vehicle, the combination of a 65 bolster-channel having raised ends to receive running-boards, a cradle-block seated in the central part of the bolster-channel, and running-board filler-blocks in the end portions of the channel having their inner portions overlapping the top of the cradle block and secured thereto.

8. In a tank vehicle, the combination of 70 sills, a bolster-channel thereon, a cradle-block seated in the bolster-channel, connections uniting the bolster channel to the sills, lugs on the channel outwardly from said 75 connections, tank-straps drawing against said lugs, and a reinforcement for the central part of the channel resisting springing thereof under the pull of the tank-straps.

9. In a tank vehicle, the combination of 80 sills, bolster members thereon, cradle-blocks on the bolster members to receive the tank, fastenings embracing the bolster members and extending downward at opposite sides of each of the sills, angle fittings bolted to the opposite sides of each of the sills with 85 their top flanges spaced below the bottoms of the bolster members, and means for drawing up on the fasteners against said top flanges of the fittings.

10. A mounting for vehicles comprising 90 the combination of sills, bolster-channels thereon, bolster-blocks seated in the bolster-channels and having slots above the top thereof and over the sills, and means for securing the bolsters to the sills comprising 95 fastenings in the slots and embracing the bolster-irons permitting variable spacing of the sills.

11. In a tank vehicle, the combination of 100 sills, bolsters comprising channels and cradle-blocks seated in the channels, the cradle-blocks being slotted in their under portions, fittings on the sills, and clamps embracing the bolster-channels within the slots of the cradle-blocks and engaging the 105 fittings on the sills.

AUGUSTINE DAVIS, Jr.
ARTHUR L. BETTS.
